UNITED STATES PATENT OFFICE.

WALDEN G. JOHNSON, OF LOS ANGELES, CALIFORNIA.

FLOOR SANDING AND POLISHING MACHINE.

1,316,841.

Specification of Letters Patent. Patented Sept. 23, 1919.

Application filed November 19, 1917. Serial No. 203,042.

To all whom it may concern:

Be it known that I, WALDEN G. JOHNSON, a subject of the King of Sweden, residing at Los Angeles, in the county of Los Angeles and State of California, have invented new and useful Improvements in Floor Sanding and Polishing Machines, of which the following is a specification.

My invention relates to sanding and polishing machines and has for a primary object the provision of a portable machine capable of use for sanding and polishing hard wood floors and of being self propelled over the floors during its operation.

15 A further object is to provide means supported on the machine for operating the sanding and polishing elements and capable of being connected to the traction wheels of the machine for imparting power from a motor thereto.

20 A further object is to provide a machine of the character referred to having a carriage upon which the sanding and polishing means may be supported and adapted to be self propelled over the floor in both forward and reverse directions at will by an operator or, operated as a stationary machine, as may be desired.

25 A further object is to provide suitable transmission means and steering means for the machine carriage by means of which the application of power may be made to the traction elements and the machine guided in desired directions.

30 A further object is to provide a machine of the character described, a blower and means leading thereto for removing all dust from the floor over which the machine traverses during its operation and means associated therewith for collecting the dust in a suitable receptacle or bag. Other objects may appear as the description progresses.

35 I have illustrated one form of machine in the drawings hereto annexed showing a preferred embodiment of my invention which I will now describe in detail, similar characters of reference being employed in the several views of the drawings for indicating the same or like parts and reference being made thereto in the specification hereinafter following.

40 Referring particularly to the drawings, Figure 1 is a side elevation of my assembled machine, Fig. 2 is a plan of the sand belt tightening means, Fig. 3 is a transverse

section of the same and Fig. 4 is a transverse section of the platform of the machine showing the support for the said tightening means. Fig. 4^a shows a modified form of tightening means. Fig. 5 is a plan of the machine, Fig. 6 is a rear end elevation of the same, Fig. 7 is a plan of the transmission means, sanding belts and shoes therefor, Fig. 8 is a side elevation of the worm gear transmission means and Fig. 9 is a view of the same, partly in section, at right angles to Fig. 8. Fig. 10 is a front end elevation of the machine, Fig. 11 is an enlarged longitudinal section of the front end of the machine, Fig. 12 is a perspective view of the sanding and polishing 60 shoes and attachments therefor and Fig. 13 is a composite section of the same. Fig. 14 is an enlarged transverse section of the steering mechanism and Fig. 15 is a longitudinal section of the same. Fig. 16 is a plan of the 65 steering bar and transmission lever.

70 In the detailed description of my device hereinafter following it will be obvious that the structure shown and described is capable of substitution and modification to a limited 75 extent without enlarging the scope or departing from the spirit of my invention.

75 Briefly described my invention consists of a carriage A having main traction wheels B and pilot wheels C, sanding and polishing 80 belts D, a motor for operating the traction wheels and polishing belts, and a blower mechanism F for collecting the dust resulting from the operation of the machine.

Carriage A includes a platform 10 having recesses 11 and 12 formed in the opposite ends thereof for receiving a pair of sand belts D operating on opposite sides of the machine. The main traction wheels B are supported on a transverse axle 13 journaled 90 in bearings 14 and 15 at opposite ends and formed on brackets 16 and 17, respectively, said brackets being suspended from and attached to the bottom of the platform 10 at points slightly to the rear of the front end 95 of the machine. The rear end of the machine is provided with a pair of pilot wheels C which are supported on an axle 18 journaled in bearings 19 formed on the lower arms of a swivel yoke 20, said yoke having a vertical 100 stem 21 with a square end 22 riveted or otherwise secured in the central portion of the yoke so as to turn therewith. The stem 21 extends upwardly through a hollow shaft 105 23 which is pivotally supported in a bracket 110

24 attached to the lower side of the platform 10 and the shaft 23 is inclosed in a tubular column 25 which is supported on the floor of the platform in a floor flange 26, the shaft 5 23 extending slightly above the upper end of the column 25, as shown in Figs. 14 and 15. The upper end of the stem 21 is attached to a ball fitting 27 having arms 28 secured therein and extending opposite directions 10 therefrom for the purpose of turning the stem and the pilot wheels beneath the platform 10. Thus the carriage A is portably mounted on the traction and pilot wheels so that it may be moved about, as hereinafter 15 more fully described.

Motor E is connected with and operates a driven pulley 28' on a transverse shaft 29 by means of a belt 30 running over the motor driven pulley 31 and the belt operating 20 through suitable apertures in the platform 10, as at 32. Driven shaft 29 is revolvably supported in bearings 33 which are adjustably held in brackets 34 depending from the bottom of the platform 10 and on opposite 25 sides thereof. Motor E is suitably mounted on a base 35 and blocks 36, so that it may be adjusted slightly in position for tightening the belt 30.

Motion is communicated to the forward 30 axle 13 which carries the main traction wheels B, by means of a longitudinal shaft 37, which is journaled in a bearing 38 suspended from the platform 10 at a point near the front of the machine and at the rear end 35 this shaft is journaled in a worm gear housing 39, which is suspended from the rear axle 29. Shaft 37 is driven by means of a worm gear 41 meshing therewith and mounted on the end of the shaft 37, both of said 40 worm gear elements being inclosed in said housing, as shown in Figs. 8 and 9, as usual. The forward end of shaft 37 carries a bevel friction pinion 42, or cone, which is adapted to engage selectively with one or the other 45 of a pair of cones 43 and 44 which may be integrally formed as shown or separate and slidably keyed to the front axle 13. Cones 43 and 44 are moved longitudinally of axle 13 by means of a yoke 45 which engages an 50 annular groove 46 formed centrally of the cones and is attached to the front end of a longitudinal clutch operating rod or shaft 47 supported at the front end in a bearing 48 integrally formed with bearing 38 of the 55 shaft 37. The rear end of clutch operating shaft 47 is pivotally held in a bearing 49 formed on the bracket 24 of the steering gear and carries a bevel gear 50 which meshes with a similar gear 51 carried on the 60 lower end of the hollow shaft 23 of the steering gear. The upper end of shaft 23 carries a clutch operating lever composed of a stationary part 52 attached to the shaft 23 by any suitable means and to which is piv-

oted a handle 53 extending horizontally 65 therefrom and adapted to seat in one of several notches 54 formed in the upper edge of a sector 55 attached to the upper end of the column 25 of the steering gear.

It will be obvious that the movement of 70 shaft 23 by means of the handle 53 in either direction from a neutral position as shown, will effect a corresponding movement of shaft 47 and yoke 45, the yoke in turn moving the cones 43 and 44 correspondingly so 75 as to engage the pinion 42. Thus either a forward or reverse motion may be imparted to the traction wheels and the traction wheels and the steering mechanism and clutch means being convenient to an operator 80 who may sit upon a seat 56 attached to the platform 10, and operation of the machine may be easily controlled.

Rear axle 29 and shaft 37 rotate continuously during the operation of the motor and 85 each end of the axle or shaft 29 carries a large and relatively wide faced pulley 57 over which the sanding and polishing belts D operate. The forward end of the belts 90 D run over small pulleys 58 which are carried on opposite ends of a transverse shaft 59 journaled in bearings 60, said bearings being capable of adjustment longitudinally of the machine for the purpose of tightening 95 the polishing belts D. The adjustment is 100 accomplished by means of horizontal slides 61, which are connected at their rear ends by means of a transverse bar 62 and have slots 63 at their front end for receiving the bearings 60, the slides being spaced at the 105 rear by means of a bar 62 and at their front by means of set collars 64 on shaft 59 adjacent to the bearings 60, and the slides having tongues 65 which slidably engage corresponding grooves 66 in a central block 110 67 attached to the bottom of the platform 10. The bar 62 is loosely attached to the 115 front end of an adjustment screw 68 which may be suitably held therein against longitudinal movement independently of the bar, and the screw 68 is threaded through a block 69 held on another cleat or block 70 attached to the lower side of the platform 10. Thus the turning of the screw 68 will effect a movement of the slides 61, shaft 59 and pulleys 58 thereon longitudinally of the machine, or separate adjusting screws may be provided for each of the pulleys 58 as shown in Fig. 4^a for tightening the belts independently.

Belts D are arranged to run in a plane 120 very close to the floor and a pair of shoes 71 are provided at the front, over which these belts run, as shown in Fig. 1. Said shoes are pivotally and adjustably suspended from the platform 10 by means of braces 72 and toggles 73 and are connected by means of cleats 74 on their rear sides. The tension 125

on the shoes may be released by means of a hand lever 72' and rods 73'. Each shoe is composed of a plurality of thicknesses of wood, as *a*, *b*, *c* and *d* which are suitably attached together for forming the upper portion of the shoe and are also attached in any suitable manner to the cleat 74. The lower portions of the shoes are substantially spaced from the upper portions just described, and are also composed of a corresponding number of sections, as at *e*, *f*, *g*, and *h*, which occupy the same vertical planes as the sections *a*, *b*, *c* and *d* of the upper portions. Sections *a*, *b*, *c* and *d* and *e*, *f*, *g* and *h*, are respectively hinged together by means of leather strips 75 and the adjacent faces thereof are bored, as at 76, to form seats for springs 77 which serve to resiliently space the blocks of the upper and lower shoe portions. An outer piece of leather 78 is provided on the outer face of the shoes over which the belts D operate, thus providing a smooth and practically frictionless surface for the belts. The shoes are positioned directly beneath the pulleys 58 and the forward faces of the shoes are rounded so as to permit the operation of the belts as close to the walls of a room as possible. For a like reason the belts D occupy positions at the extreme sides of the platform, as shown, so that the machine may be run close up to the walls at the sides. The cleat 74 of the shoes only engages the rear ends of the blocks of the lower shoe portions and by means of the springs 77 independent action is afforded the different sections of the shoes so as to compensate for the unevenness of the floor over which the machine operates. The springs should, however, be sufficiently strong as to hold the belts D firmly against the floor for obtaining the best results.

The belts D operate over the top of the platform 10 from the rear to the front, thence downwardly over pulleys 58 and shoes 71, thence in contact with the floor and over rear pulleys 57, and the dust which is formed in the sanding or polishing operation is carried over the floor beneath the belts to the rear of the machine where it is sucked up into the two flattened ends 80 of a blower pipe 81 leading to and connected with the inlet 82 of a centrifugal blower 83, the ends 80 of said pipe being curved as shown in Fig. 1 to conform to the periphery of the pulleys 57 and terminating at points close to the floor.

The blower 83 is suitably supported on a raised shelf 84 above the main platform and is arranged to discharge the dust into a bag 60 of receptacle 85 connected with the outlet of the blower by means of a pipe 87.

The traction wheels of the machine are positioned between the belts D and intermediate of the ends of the platform so that they

in no way interfere with the operation of 65 the belts and the driving shaft 37 is straddled by the steering yoke, so that the pilot wheels may be operated to a sufficient extent to accomplish a complete turn of the machine.

In operation, the mechanism is started and the machine is guided over the floor in a straight path and if necessary returned over the same path until the floor is sufficiently smooth, whereafter the machine is guided 70 into another plane of action adjacent to the one just traversed and finished, and so on until the entire floor shall have been finished. At certain rough points in the floor the propelling mechanism may be disconnected 75 from the traction wheels and the machine held stationary above such points until the rough places shall have been removed, after which the machine may proceed in a desired path. It will be understood that the machine is designed to move at a very slow speed over the floor but the blower which is 80 operated by a belt 88 operating over the driving belt of the machine and the relatively small pulley 89 of the blower, is designed to operate at a rapid speed so as to insure the removal of the dust from the floor. The speed of the sand belts should be moderately rapid for good results.

By loosening the belt adjusting means described, the sand belts may be quickly removed from their pulleys and replaced by other belts from time to time as needed. The blower suction pipes may be also quickly removed from their connection with 100 the blower when the sand belts are removed, the lower ends of the blower pipes being supported loosely on the upper side of the platform by means of straps 90.

The shoes 71, when the machine is idle, 105 may be raised slightly from the floor and the belts D slightly loosened on their pulleys by moving the hand lever 72' forward, the connecting rods 73' attached to the toggle levers serving to move the shoes slightly 110 backward and upward when the machine is started and the belts D are in operation, the lever 72' may be moved backwardly and locked by a suitable ratchet and sector, as shown, for holding the shoes firmly against 115 the belts and placing tensions on the belts.

A hand block 91, as shown in broken lines in Fig. 1, may be used in lieu of the shoes 71, the block being held in the hand of the operator against the inner side of one of the 120 belts D for pressing the belts against the floor, where such may be necessary for a perfect finish.

What I claim is:

1. A floor finishing machine including a 125 belt like abrasive element, means for moving said element over the floor, a plurality of resiliently supported elements en-

- gaging said belt for forcing said belt into engagement with the floor during the finishing operation, and means for pivotally retracting said elements, for loosening said belt.
5. A floor finishing machine including movable polishing belt means for engagement with the floor to be finished, and a plurality of non-rotatable and resiliently supported elements engaging the inner side of and adapted to hold said belt in frictional engagement with the floor.
10. A floor finishing machine comprising a portable carriage having motor operated abrasive belt means held thereon for contact with the floor, a plurality of independently resilient and yieldable members engaging said belt means and for holding the same in frictional contact with the floor, means for releasing said members from said belt, and transmission means for moving said carriage over said floor.
15. A floor finishing machine comprising a carriage having a motor thereon, abrasive belt means traversing the length of and positioned on opposite sides of said carriage and operated by said motor, a resilient shoe engaging said belt means at one end for maintaining the frictional engagement of said belt with the floor, and means at the opposite end of said belt for collecting the dust produced by said belt and removing the same from the finished floor.
20. A floor finishing machine comprising a portable carriage having a pair of longitudinally movable abrasive belts operably supported on opposite sides and traversing the length thereof, a yieldable shoe engaging said abrasive element at one end of said carriage for holding said element in frictional contact with the floor, means for releasing said shoe from said belt, steering means and traction means for said carriage, and common operating means for said abrasive elements and said traction means.
25. A floor finishing machine comprising a power driven carriage provided with a motor, steering and traction means therefor, transmission means connecting said traction means with said motor for forward and reverse movement, a driven shaft at each end of said carriage, pulleys on said shafts, a movable frame for adjusting one of said shafts relative to the other, abrasive belt means operably connecting said pulleys for frictional engagement with the floor, a shoe for holding said belt in contact with the
- floor, and means for raising said shoe for loosening said belt.
30. A floor finishing machine comprising a base having traction wheels and steering means therefor, transmission means for said traction wheels, a motor for operating said transmission means, abrasive belt means traversing the length of said base and for engagement with the floor, means for operably connecting said belt means with said transmission means, and a resiliently held shoe for frictionally engaging said belt means with said floor.
35. A floor finishing machine comprising a dirigible carriage provided with self contained transmission means, a pair of rotatable shafts suspended therefrom having pulleys thereon, said pulleys being held at different elevations, means for relatively adjusting said shafts, abrasive belt means operably connecting said pulleys longitudinally of said carriage for frictionally engaging the floor, and means for connecting said belts for operation by said transmission means.
40. A floor finishing machine comprising a dirigible carriage having a motor thereon and motor propelled traction wheels for supporting said carriage on the floor to be finished, a motor driven shaft disposed laterally of said carriage, an idler shaft in alignment and relatively adjustable thereto, an abrasive belt operated by said driven shaft and serving to operate said idler shaft and for engagement with the floor, a shoe held beneath said idler shaft for yieldably holding said belt in engagement with the floor during the finishing operation.
45. A floor finishing machine comprising a portable carriage having a motor thereon, traction wheels and steering means therefor, a pair of driven shafts disposed in alignment at opposite ends of said carriage and having pulleys thereon, one of said pulleys being raised substantially above the surface to be polished, said shafts being relatively adjustable, abrasive belt means operably connecting said pulleys longitudinally of the carriage, a yieldable shoe supported beneath said raised pulley for holding said belt means in frictional engagement with the floor to be finished, and suction means at one end of said belt means for collecting the dust and the like produced by said belt means in the operation of the machine.

WALDEN G. JOHNSON.
